FIG. 5.

UNITED STATES PATENT OFFICE.

WILLIAM R. PARK, OF TAUNTON, AND BELVIN T. WILLISTON, OF SOMERVILLE, MASSACHUSETTS, ASSIGNORS TO THE HANCOCK INSPIRATOR COMPANY, OF BOSTON, MASSACHUSETTS.

VALVE.

SPECIFICATION forming part of Letters Patent No. 587,855, dated August 10, 1897.

Application filed July 28, 1896. Serial No. 600,810. (No model.)

To all whom it may concern:

Be it known that we, WILLIAM R. PARK, residing at Taunton, in the county of Bristol, and BELVIN T. WILLISTON, residing at Somerville, in the county of Middlesex, State of Massachusetts, have invented an Improvement in Valves, of which the following description, in connection with the accompanying drawings, is a specification, like letters on 10 on the drawings representing like parts.

This invention relates to an improvement in valves, and has for its object to provide a valve which is detachably secured to its stem in a manner as will be described, so that the 15 valve is free to adapt itself to irregularities in its seat and yet is so attached to its stem that it may be ground while on the stem.

In accordance with this invention the valve is attached to its stem by movement of one 20 part laterally with relation to the other part, and the said parts when in alinement with each other are locked against lateral movement by an intermediate device, as will be described. These and other features of this 25 invention will be pointed out in the claims at the end of this specification.

Figure 1 represents in elevation a valve and its stem embodying this invention. Fig. 2 is a longitudinal section of the valve and 30 its stem shown in Fig. 1; Fig. 3, a perspective of the valve, intermediate device, and stem separated; and Fig. 4, a modification to be referred to.

Referring to the drawings, A represents a 35 valve, and A' a stem to which the valve is detachably secured by an intermediate device, preferably of the construction herein shown.

The intermediate device referred to may 40 and preferably will be made in the form of an internally-threaded nut a, which is adapted to engage a threaded stud or projection a' on the back face of the valve A. The nut a is provided with substantially diametrically opposite arms or lugs b b', having inwardly-projecting flanges b² b³, forming locking-fingers, which are adapted to fit over projections b⁶ b⁷ on the reduced portion or end b⁸ of the valve-stem. 45 The projections b⁶ b⁷ may and preferably will 50 be integral with the valve-stem A', and may

be formed by shaping or cutting away the valve-stem at substantially diametrically opposite points or sides, as shown in Fig. 3. The arms b b' and their flanges b² b³ are made of such size as will leave passage-ways c³ c⁴ 55 between the under-side of the said flanges and the upper surface of the nut of a depth substantially equal to the thickness of the projections b⁶ b⁷ on the stem, so that the stem may be disconnected from the valve, and vice 60 versa, when the stem is permitted to be moved laterally.

The nut a, provided with the arms b b', having the inwardly-projecting flanges or fingers, forms one form of intermediate device by 65 which the valve is attached to the valve-stem, and the said valve and stem may be locked against lateral movement, one with relation to the other, by providing the flanges b² b³ on their under side with substantially circular 70 recesses b⁴ b⁵ for the reception of the projections b⁶ b⁷ on the valve-stem, in which recesses the said projections are retained by means of the stud a' on the valve by turning the said nut on the stud a', so as to force the 75 projections b⁶ b⁷ into said recesses and into the position shown in Fig. 2. When the stud a' occupies the position shown in Fig. 2, its upper surface is above the lower edge of the side walls of the recesses b⁴ b⁵, and consequently 80 the valve-stem cannot be moved laterally to disconnect it from the valve, and vice versa, until the nut is turned, (the valve being held stationary,) so as to carry the nut on the stud a' away from the valve a sufficient distance 85 to permit the projections b⁶ b⁷ to pass under the side walls of the recesses b⁴ b⁵. When the parts occupy the position shown in Figs. 1 and 2, the valve is securely attached to its valve-stem, but the attachment is sufficiently 90 loose to permit the valve to wobble and thereby adjust itself to irregularities on its seat.

As shown in Figs. 1, 2, and 3, the flanges b⁶ b⁷ on the stem are located diametrically opposite, and the reduced portion b⁸ of the stem 95 is of a length greater than the width of the slot or passage-way between the locking-fingers b² b³, but we do not desire to limit our invention in this respect, as the reduced portion b⁸ of the valve may be made of a diam- 100

eter or width less than the width of the slot between the fingers b^2 b^3 , and the flanges b^6 b^7 may be united and made in the form of a disk f on the end of the valve-stem, as shown 5 in Fig. 4.

We claim—

1. The combination with a valve provided with a stud, a valve-stem provided with a web having lateral projections, and a nut having 10 separated arms provided with fingers forming a passage into which the said web is introduced laterally, and passage-ways for the reception of the lateral projections on the stem, and means to confine said projections 15 in their passage-ways, substantially as described.
2. The combination of a valve having a threaded stud, a nut to engage said stud, arms on said nut located substantially oppo-

site and provided with flanges extended to- 20 ward each other to form a passage, and provided on their under-sides with recesses having end walls, a valve-stem provided with a web adapted to pass between the said flanges, and lateral projections on said web adapted 25 to enter the said recesses and be retained therein against longitudinal movement by the said stud, and against lateral movement by the said end walls; substantially as de- scribed.

In testimony whereof we have signed our names to this specification in the presence of two subscribing witnesses.

WILLIAM R. PARK.
BELVIN T. WILLISTON.
